Patented Aug. 7, 1962

193,339

FURNITURE BASE

Charles Eames, Venice, Calif., assignor to Herman Miller,
Inc., Zeeland, Mich., a corporation of Michigan

Filed May 23, 1961, Ser. No. 65,286

Term of patent 14 years

(Cl. D15—1)

FIG. 1 is a perspective view of my design for a furniture base.

FIG. 2 is a cross-sectional view taken along line II—II of FIG. 1.

FIG. 3 is a side elevation of the furniture base of FIG. 1.

FIG. 4 is a cross-sectional view taken along line IV—IV of FIG. 1.

FIG. 5 is a cross-sectional view taken along line V—V of FIG. 3.

FIG. 6 is a cross-sectional view taken along line VI—VI of FIG. 1.

FIG. 7 is a cross-sectional view taken along line VII—VII of FIG. 1.

FIG. 8 is a cross-sectional view taken along line VIII—VIII of FIG. 1.

The dotted lines of FIGURE 1 are for illustrative purposes only.

I claim:

The ornamental design for a furniture base, substantially as shown and described.
